Patented Dec. 7, 1926.

UNITED STATES PATENT OFFICE.

HENRY M. LAMBERT, OF PORTLAND, OREGON, ASSIGNOR TO LAMBERT TIRE & RUBBER CO., OF BARBERTON, OHIO, A CORPORATION OF ARIZONA.

BORING MACHINE.

Application filed July 2, 1924. Serial No. 723,787.

The invention generally relates to boring machines and more particularly to that class of such machines in which means is provided for boring a plurality of holes simultaneously.

The invention generally seeks to provide a machine of the type stated particularly adaptable to use in boring the annularly arranged cross holes of the well-known "Trublpruf" cushion tires.

The invention further seeks to provide a machine of the type stated, which is relatively simple and economic of construction, and which is easily operable for the purpose of simultaneously boring all of the annularly and closely arranged cross holes of the tires mentioned, in an efficiently effective manner; thus contributing greatly to the uniformity and economy of manufacture of the product mentioned.

In its more detailed nature, the invention further comprehends means whereby the machine may be adapted to the boring of cross holes in varied sizes of tires, to provide for the boring of the holes in close relation, for effectively positioning the tire to be bored, for removing the bored plugs, and for water-lubricating the boring action.

With the above and other objects in view, the invention still further resides in those novel details of construction, combination and arrangement of parts, all of which will be first fully described, then be particularly pointed out in the appended claims, reference being had to the accompanying drawings, in which:

Figure 1 is a central vertical cross section of the machine.

Figure 2 is a horizontal section on the line 40 2-2 on Figure 1.

Figure 3 is a plan view of a portion of the removable ring gear.

Figure 4 is a detail cross section of the gear part shown in Figure 3.

Figure 5 is a plan view of a portion of the gear carrying plate.

Figure 6 is a detail cross section of the gear part shown in Figure 5.

Figure 7 is an inverted plan view of a portion of the plunger securing ring.

Figure 8 is a detail cross section of the ring part shown in Figure 7, one of the securing clamps being also shown.

Figure 9 is a side elevation, parts being broken away and in section, showing the removable boring sleeve feature.

Figure 10 is a detail perspective view illustrating the end structure of the core removing plunger.

Figure 11 is a detail section illustrating the means for adjustably securing the ring plates to position supported by the uprights.

In carrying out my invention, I utilize four uprights or corner posts 1 which may be either circular or square in cross section and embedded in a suitable base 2 to secure the same to the vertical position illustrated. The base 2 serves to support a hydraulic cylinder 3, and a fluid connection 4 is provided for admitting fluid under pressure into the

bottom of the said cylinder, a piston or plunger 5 being provided to slidably fit the cylinder 3 so that when fluid under pressure is admitted in the connection 4 it will act against the said plunger to lift the same and the supporting and lifting table 6 secured thereto, as shown. In Figure 1, a tire, represented by the numeral 7, is shown as resting upon the table 6 in position for being lifted thereby into engagement with the boring elements later described for having cross holes bored therethrough to form the well-known Lambert "Trublpruf" cushion tire.

As will later be apparent, the boring elements are preferably such that they will remove plugs from the tire stock in forming the cross apertures, and it is also preferred that the boring action take place prior to vulcanization of the built-up tire stock so that the plugs bored therefrom may be again used, although it should be understood that the machine may be used to bore the cross apertures through otherwise completed tire bodies.

Bearing portions 8 for surrounding the uprights 1 to aid in guiding the movement of the said table are provided in the extended ears 9 of that table, and the said ears are connected by the vertical rod connections 10 to the ears 11 of the plunger carrying head

ring 12. Thus, the table 6 and the ring 12 are joined to move together in spaced relation for a purpose later to be described.

A plate head 13 is secured to the upper ends of the uprights 1 and the said plate is provided with a dependent bearing head 14 which provides a suitable bearing for the drive shaft 15 upon the upper end of which is secured a large bevelled gear 16 to which 5 rotary motion is imparted by reason of having the small bevelled pinion 17, upon the horizontally disposed drive shaft 18, mesh therewith. A gear carrying plate 19 is secured to the bottom end of the drive shaft 10 15 and the said plate is provided with drive lugs 20 adapted to fit into the similarly shaped cut out portions 21 formed on the removable ring gear 22, which is removably connected to the said carrying plate 19 by 20 the slide bolt connections 23, see Figures 1 and 3 to 6 inclusive.

The ring gear 22 is adapted to mesh with the plurality of small pinion gears 24 secured upon the boring elements 25 in the manner and position illustrated in Figures 25 1 and 2 of the drawings. From the figures referred to, it will be observed that the said boring elements and pinions are positioned vertically and spaced with their axes in a 30 annular formation so as to be in position for effecting the boring of the cross apertures through the tire 7 positioned horizontally as 35 illustrated in the said Figure 1, when the same is elevated into engagement with the said boring elements by the table 6. It will also be observed by reference to the said figures, especially Figure 2, that the pinions 24 are lap arranged so that the axes thereof may be closely adjacent one to another, 40 the said pinions being alternately lapped as shown. This peculiar arrangement of the pinions makes it possible to bore the cross apertures in the tire in closely adjacent relation in the manner desired in tires of the 45 class stated, as exemplified by the well-known Lambert "Trublpruf" cushion tire.

Suitable bearings are provided for the 50 boring elements 25 in the upper and lower ring plates 26, which are secured together in spaced relation, as at 27, and which have extended ears having bearing against the uprights 1. Each of the extended ears 28 of one of the plates 26 is supported upon a supporting bolt 29 which passes through a suitable aperture provided therefor in the respective upright 1 and which includes an upturned and threaded portion adapted to pass through an accommodating aperture in the 55 said ear and to be nut-secured as at 30 so as to support the said rings against displacement to thereby form a rigid bearing for the said boring elements. Rest collars 31 may be provided and secured upon the boring sleeves to engage the bearings provided 60 therefor in the plates 26 and positioned be-

tween the said plates so as to support the said boring elements and the pinions with which the same are equipped in a rotatable manner against vertical displacement during the boring action. 70

A tire aligning ring 32 is provided and sustained in a vertically movable manner from the lowermost plate 26 through the medium of the chain connections 33. The plate is provided with apertures through which 75 the lower ends of the boring elements 25 project and aligning lugs 34. The ring 32 also includes extended ears 35 which engage the uprights 1 so that when the table 6 is elevated to lift the tire 7 into engagement 80 with the boring elements, the centering lugs 34 will engage the rim of the tire to effectively center the same to the desired position so that a perfect boring action may be had. 85

The boring elements 25 are in the nature of hollow tubes and a core removing plunger 36 is slidably mounted within each said boring element. A core plunger securing ring 37 is provided, the inner edge diameter 90 thereof, indicated at 38, being slightly larger than the peripheral diameter of the gear carrying plate 19 so that the said ring 37 may be readily applied over the same without removing it from its connection with the drive 95 shaft 15. Clamps 39 are provided for securing the ring 37 to tight engagement with the bottom surface of the ring 12, suitable set screw connections 40 being provided for that purpose. 100

The ring 37 is provided with a plurality, one for each plunger and boring element, of depending hubs 41, which are apertured to receive the uppermost ends of the plungers 36, set screws 42 being provided for securing the said plunger ends within the said hubs. Thus, it will be seen that the plungers are connected, through the rings 37 and 12 and the clamps 39 and the rod connections 10, with the table 6, so that the said connections 110 and the plungers will be moved in unison with the said table. The ring 37 is provided with an annular water trough 43, and a water trough 44 is provided on the ring 12, communicating apertures 45 being provided 115 in the ring 12 to effect water communication from the trough 44 into the trough 43 and the hollow of the tubular plungers 36 and boring elements 25 so as to water-lubricate the boring action, it being experienced in 120 practice that in cutting rubber, the cutting action is much more efficient when water-lubricated.

Obviously, it will be desired to bore cross apertures in varied sizes of tires, and for this 125 reason the radius of the axes of the plungers and boring elements must be changed relative to the radius of the tire to be bored. For this reason, the ring 37, plungers 36, pinions 24, boring elements 25, ring plates 130

26 and the aligning plate 32 and also the ring gear 22 are removable to be replaced by like equipment of dimensions for effecting the boring of the desired diameter of tire. 5 In other words the parts mentioned are readily removable for replacement.

Operation.

In operation, the tire 7 is placed upon the 10 table 6 and fluid under pressure admitted into the cylinder 3 through the connection 4, thus effecting a raising of the table and a lifting of the tire 7 carried thereby upward toward engagement with the boring elements. 15 As the tire is brought up almost to engagement with the cutting ends of the boring elements 25, the same will be engaged by the aligning lugs 34 to be properly centered thereby, if not so positioned already. 20 The gears 16 and 17 being active, rotary motion is imparted to the ring gear 22 and therethrough and through the pinions 24 to the boring elements 25. As the lifting action is continued the boring action progresses, the centering plate 32 being lifted with the tire during such action.

When the boring action has been completed, the lifting of the table 6 will, of course, be stopped, and the table permitted 30 to descend again to the normal position, it being understood that a suitable wear plate may be mounted upon the table 6 beneath the tire so that the boring elements 25 will not be injured when passing through the 35 said tire a slight distance in completing the boring action.

While it is possible that the boring elements could be constructed of the auger type, it is preferred to form the cross apertures by removing plugs therefrom and this is accomplished by forming the boring elements tubular so that the plug removed thereby will be forced up into the said boring elements during the boring action.

45 As the table 6 lifts the tire into engagement with the boring elements 25, it simultaneously effects lifting of the plug removing plungers 36 within the said boring elements by reason of the connections 10, 12, 37 and 42 50 and when the boring action has been completed and the table again lowered, the plungers are likewise lowered and come in contact with the bored plugs within the ends of the boring elements and effectively eject 55 the same therefrom. In Figure 11 of the drawings is illustrated an enlarged detail of one suitable means for supporting the ring plates 36, the same embodying the bolt and nut connections 29 and 30 hereinbefore described, suitable apertures 46 being provided 60 in the uprights 1 so that the position of the said plates may be adjusted, if desired.

The plug engaging ends of the plungers 36 may be bit shaped, as at 47 if desired, 65 see Figure 10 of the drawings.

While it would be practical to construct the boring elements in the manner illustrated in the figures of the drawings referred to, it may be found very desirable to provide boring sleeves readily removable from the 70 boring elements and I have illustrated one means of providing such a feature in Figure 9 of the drawings, in which the lower end of the boring element 25 is shown provided with a pin 48 adapted to connect with 75 the bayonet slot 49 of a boring sleeve 50, which may be thereby readily attached to or removed from the said boring element for the purpose of sharpening, cleaning, or the like. In using a boring sleeve such as described, it should be understood that the bayonet slot 49 will be directed in consideration of the direction of rotation of the boring elements 25 so that disengagement of the parts during boring action would not be 85 possible.

In the drawings, I have illustrated one embodiment of the various features of the invention and it is to be understood that various changes of structure and details of 90 arrangement may be made without departing from the scope of the invention as particularly pointed out in the appended claims, and it is believed that from the disclosure of these drawings and the detailed description, the principles of the invention, manner of arrangement of the cooperative parts, the manner of operation, and the advantages thereof will be readily apparent to 95 those skilled in the art to which it relates. 100

What I claim is:

1. In a tire boring machine, a plurality of boring elements, power transmission means for rotating the boring elements simultaneously, means for changing the relative 105 positions of the thing to be bored and the boring elements to effect the boring action, and means for delivering water lubricant simultaneously through the several cutting elements to their cutting ends. 110

2. In a machine of the class described, a plurality of boring elements, power transmission means for rotating the boring elements, means for lifting the thing to be bored into engagement with the boring elements to cause the same to bore plugs therefrom, and means movable with said lifting means and active on the lowering or return movement of the lifting means for ejecting 115 the plugs from the ends of the boring elements. 120

3. In a machine of the character described, a plurality of boring elements, pinions mounted thereon, a gear carrying plate, a driving gear for engaging all of the pinions 125 to impart rotation to the boring elements simultaneously, means removably mounting the driving gear upon said carrying plate, means for driving said carrying plate, and means for changing the relative positions 130

of the thing to be bored and the boring elements to effect the boring action.

4. In a machine of the class described, a plurality of boring elements, pinions mounted on the boring elements and lap arranged to permit close relation, a driving gear for engaging all of the pinions to impart rotation to the cutting elements simultaneously, the said driving gear having driving lugs, 10 a carrying plate having driving lugs for engaging those of the driving gear and slide bolts for securing the said gear thereto, a driving shaft for carrying and rotating the carrying plate, and means for changing the 15 relative positions of the thing to be bored and the boring elements to effect the boring action.
5. In a machine of the class described, a plurality of tubular boring elements, pinions mounted on the boring elements and lap arranged to permit close relation, a driving gear for engaging all of the pinions to impart rotation to the cutting elements simultaneously, means for lifting the thing 20 to be bored into engagement with the boring elements to cause the same to bore plugs therefrom, and plungers movable centrally by and with the lifting means through the boring elements and active during the 25 return movement of the means for lifting the thing to be bored for removing the plugs from the ends of the boring elements.
6. In a machine of the class described, a plurality of boring elements, pinions mounted 30 on the boring elements and lap arranged to permit close relation, a driving gear for engaging all of the pinions to impart rotation to the cutting elements simultaneously, means for lifting the thing to be bored into engagement with the boring elements to cause the same to bore plugs therefrom, plungers connected to and moved by the lifting means and movable centrally through 35 the boring elements and active during the return movement of the lifting means for removing the plugs from the ends of the boring elements, and means for passing water 40 into the boring elements through said plungers to water-lubricate the working ends of the boring elements.
7. In a machine of the class described, a plurality of boring elements, power transmission means for rotating the boring elements, means for lifting the thing to be bored into engagement with the boring elements to cause the same to bore plugs therefrom, plungers connected with and movable by the lifting means and movable centrally through 45 the boring elements and active during the return movement of the lifting means for removing the plugs from the ends of the boring elements, and means for passing water into the boring elements and plungers 50 to water-lubricate the working ends of the boring elements.

8. In a machine of the class described, a plurality of boring elements, power transmission means for rotating the boring elements, means for lifting the thing to be bored into engagement with the boring elements to cause the same to bore plugs therefrom, means for centering the thing to be bored effective during the lifting action, and means connected to move with said lifting means and active on the lower or return movement of the lifting means for removing the plugs from the ends of the boring elements. 70

9. In a machine for boring rubber tires and the like, a plurality of boring elements, power transmission means for rotating the boring elements, means for lifting the thing to be bored into engagement with the boring elements to cause the same to bore plugs therefrom, means for centering the thing to be bored effective during the lifting action, the said centering means comprising a vertically movable plate having centering lugs and through which the boring elements project, and means associated with and active on the lowering or return movement of the lifting means for removing the plugs from the ends of the boring elements. 80

10. In a machine of the class described, a plurality of boring elements, power transmission means for rotating the boring elements, means for lifting the thing to be bored into engagement with the boring elements to cause the same to bore plugs therefrom, plungers movable centrally through the boring elements, associated with and active during the return movement of the lifting means for removing the plugs from the ends of the boring elements, the said plungers and the said lifting means being connected to lift and lower in unison. 90

11. In a machine of the class described, a plurality of annularly-vertically arranged tubular cutting elements, a table for lifting the tire into engagement with the cutting elements, rings for carrying and providing bearings for the cutting elements, supports upon which the rings are removably mounted and for guiding movement of the table, pinions on the boring elements and lap arranged to permit close rotation, and a driving gear for engaging all of the pinions to impart rotation to the cutting elements simultaneously. 100

12. In a machine of the class described, a plurality of annularly-vertically arranged tubular cutting elements, a table for lifting the tire into engagement with the cutting elements, rings for carrying and providing bearings for the cutting elements, supports upon which the rings are removably mounted and for guiding movement of the table, pinions on the boring elements and lap arranged to permit close relation, a driving gear for engaging all of the pinions to im- 110 115 120 125 130

part rotation to the cutting elements simultaneously, and means for centering the tire relative to the cutting elements and effective during the lifting action.

5 13. In a machine of the class described, a plurality of tubular cutting elements, a table for lifting the tire into engagement with the cutting elements, rings for carrying and providing bearings for the cutting elements, 70 supports upon which the rings are removably mounted and for guiding movement of the table, pinions on the boring elements, a driving gear for engaging all of the pinions to impart rotation to the cutting elements simultaneously, means for centering the tire relative to the cutting elements and effective during the lifting action, the said centering means comprising a plate suspended vertically-movably from the said 75 15 rings and having centering lugs and apertures through which the cutting elements project.

14. In a machine of the class described, a plurality of tubular cutting elements, a table for lifting the tire into engagement with the cutting elements, rings for carrying and providing bearings for the cutting elements, supports upon which the rings are removably mounted and for guiding movement 80 20 of the table, pinions on the boring elements, a driving gear for engaging all of the pinions to impart rotation to the cutting elements simultaneously, the said driving gear having driving lugs, a carrying plate having driving lugs for engaging those of the driving gear and slide bolts for securing the said gear thereto, and a driving shaft for carrying and rotating the carrying plate.

15. In a machine of the class described, a plurality of tubular cutting elements, a table for lifting the tire into engagement with the cutting elements, rings for carrying and providing bearings for the cutting elements, supports upon which the rings are removably mounted and for guiding movement of the table, pinions on the boring elements, a driving gear for engaging all of the pinions to impart rotation to the cutting elements simultaneously, and plungers movable centrally through the boring elements and active during the return movement of the lifting table for removing the bored plugs from the ends of the boring elements.

16. In a machine of the class described, a plurality of tubular cutting elements, a table for lifting the tire into engagement with the cutting elements, rings for carrying and providing bearings for the cutting elements, supports upon which the rings are removably mounted and for guiding movement of the table, pinions on the boring elements, a driving gear for engaging all of the pinions to impart rotation to the cutting elements simultaneously, and plungers movable centrally through the boring elements and con-

nected with to move in unison with the table so as to eject the bored plugs from the ends of the boring elements during the return movement of that table.

17. In a machine of the class described, a plurality of tubular cutting elements, a table for lifting the tire into engagement with the cutting elements, rings for carrying and providing bearings for the cutting elements, supports upon which the rings are removably mounted and for guiding movement of the table, pinions on the boring elements, a driving gear for engaging all of the pinions to impart rotation to the cutting elements simultaneously, hollow plungers movable centrally through the boring elements and connected with to move in unison with the table so as to eject the bored plugs from the ends of the boring elements during the return movement of that table, and means for so connecting the plungers and table including rings to which the plungers are secured and which include water passages through which water may flow into the hollow plungers and the boring elements to 90 water-lubricate the boring action.

18. In a machine of the class described, a plurality of tubular cutting elements, a table for lifting the tire into engagement with the cutting elements, rings for carrying and providing bearings for the cutting elements, supports upon which the rings are removably mounted and for guiding movement of the table, pinions on the boring elements, a driving gear for engaging all of the pinions to impart rotation to the cutting elements simultaneously, hollow ejector plungers movable centrally through the boring elements, and means for connecting the plungers and table to move in unison, said means including a carrying ring and a securing ring removably secured thereto and to which the said plungers are secured, the said rings having water passages through which water may flow into the hollow plungers and the boring elements to 95 100 water-lubricate the boring action.

19. In a machine of the class described, a plurality of tubular cutting elements, a table for lifting the tire into engagement with the cutting elements, rings for carrying and providing bearings for the cutting elements, supports upon which the rings are removably mounted and for guiding movement of the table, pinions on the boring elements, a driving gear for engaging all of the pinions to impart rotation to the cutting elements simultaneously, the said driving gear having driving lugs, a carrying plate having driving lugs for engaging those of the driving gear and side bolts for securing the said gear thereto, a driving shaft for carrying and rotating the carrying plate, hollow plungers movable centrally through 110 115 120 125 130 the boring elements and connected with to

move in unison with the table so as to eject the bored plugs from the ends of the boring elements during the return movement of that table, and means for so connecting the 5 plunger and table including a carrying ring and a securing ring removably secured thereto and to which the said plungers are secured, the said rings having water passages through which water may flow into the hollow plungers and the boring elements to water-lubricate the boring action.

20. In a boring machine, a tubular boring rod, a tubular bit removably mounted on one end of said rod as an extension thereof, an 15 ejector plunger mounted in said rod and adapted to have longitudinal movement therein and project through the bit, said plunger being of a lesser external diameter than the internal diameter of the bit to leave 20 a space between the same and means for passing water lubricant through the tubular boring rod and the plunger.

21. In a boring machine, a tubular boring rod, a tubular bit removably mounted on 25 one end of said rod as an extension thereof, an ejector plunger mounted in said rod and adapted to have longitudinal movement therein and project through the bit, said plunger having its active end bifurcated and 30 means for passing water lubricant through the tubular boring rod and the plunger.

22. In a tire boring machine, the combination with a bed for supporting the tire, a tubular drill for coring out a plug from 35 the tire, means for raising and lowering the tire supporting bed to bring the tire into and out of association with said tubular drill and means associated with the movement of the bed away from the drill for ejecting the core 40 removed by the drill.

23. A machine for boring solid rubber tire blanks which comprises a table to receive the tire blanks, a relatively fixed set of boring tools mounted above the table, fixed vertical guides, a boring tool carrier mounted 45 on said guides to sustain said boring tools, a drive shaft with master gear, pinions on said boring tools to mesh with said master gear, said boring tools comprising hollow spindles, plungers held in said spindles and adapted to project through the same, a plunger carrier located above said spindles to which said plungers are secured, connections between said plunger carrier and said table whereby movement of the table toward and from the boring tools will effect movement of said plungers whereby as said table is elevated to bring the tire carcass into operative engagement with said spindles said plungers will be withdrawn from the cutting ends of the spindles and when said table is moved in the opposite direction said plungers will be moved to eject the cores from the spindles, a centering ring and drill guide slidable on said vertical guides and having passages for said spindles, said ring having centering lugs to engage the tire blank, and means for yieldably suspending said centering ring and drill guide from said drill carrier.

50 gear, said boring tools comprising hollow spindles, plungers held in said spindles and adapted to project through the same, a plunger carrier located above said spindles to which said plungers are secured, connections between said plunger carrier and said table whereby movement of the table toward and from the boring tools will effect movement of said plungers whereby as said table is elevated to bring the tire carcass into operative engagement with said spindles said plungers will be withdrawn from the cutting ends of the spindles and when said table is moved in the opposite direction said plungers will be moved to eject the cores from the spindles, substantially as shown and described.

55 24. A machine for boring solid rubber tire blanks, which comprises a table to receive the tire blank, a relatively fixed set of boring tools mounted above the table, fixed vertical guides, a boring tool carrier mounted on said guides to sustain said boring tools, a drive shaft with master gear, pinions on said boring tools to mesh with said master gear, said boring tools comprising hollow spindles, plungers held in said spindles and 60 adapted to project through the same, a plunger carrier located above said spindles to which said plungers are secured, connections between said plunger carrier and said table whereby movement of the table toward and from the boring tools will effect movement of said plungers whereby as said table is elevated to bring the tire carcass into operative engagement with said spindles said plungers will be withdrawn from the cutting ends of the spindles and when said table is moved in the opposite direction said plungers will be moved to eject the cores from the spindles, a centering ring and drill guide slidable on said vertical guides and 65 having passages for said spindles, said ring having centering lugs to engage the tire blank, and means for yieldably suspending said centering ring and drill guide from said drill carrier.

HENRY M. LAMBERT.
